UNITED STATES PATENT OFFICE.

VACLAV FINGOUST, OF CLARKS MILLS, WISCONSIN.

WAGON-BRAKE.

SPECIFICATION forming part of Letters Patent No. 758,308, dated April 26, 1904.

Application filed February 11, 1903. Serial No. 142,979. (No model.)

To all whom it may concern:

Be it known that I, VACLAV FINGOUST, a citizen of the United States, residing at Clarks Mills, in the county of Manitowoc and State 5 of Wisconsin, have invented certain new and useful Improvements in Wagon-Brakes; and I do hereby declare, that the following is a full, clear, and exact description thereof.

My invention has for its object to provide 10 simple economical wagon-brake mechanism designed to be set by the holding back of a team of horses in connection therewith, especially when descending inclinations of roads; and it consists in certain peculiarities of construction and combination of parts hereinafter 15 particularly set forth with reference to the accompanying drawings, and subsequently claimed.

Figure 1 of the drawings represents a plan 20 view of brake mechanism in accordance with my invention applied in connection with the front truck and pole of an ordinary wagon, the pole being partly shown by dotted lines; Fig. 2, a partly sectional elevation of the same 25 viewed from the side; Fig. 3, a perspective view of the forward end of the wagon-pole and parts of the brake mechanism in connection therewith, and Fig. 4 a front elevation of what is shown in the first figure.

Referring by letter to the drawings, I indicates a brake-beam provided with shoes K 30 and having loose play in hangers P, suspended from the hounds of the front truck of a wagon. Attached to the brake-beam are links G, and a bolt Q connects the forward ends of the 35 links with rear upper ends of crooked levers F, that are fulcrumed on the pivot-bolt D, connecting the pole A of the wagon with the hounds aforesaid, the lower forward ends of 40 the levers being connected by a bolt R with rear branches of a forked rod E, having sliding support in hangers U, depending from said pole.

The forked forward end of the rod E is engaged by a link L, that connects a pair of short chains in connection with a neck-yoke B, and said link is also at times in engagement with a ratchet-bar N, made fast on the upper side 45 of the wagon-pole at the forward end of same. Straps i are employed to connect the neck-

yoke with the harness of horses hitched to the wagon, and a roller M is supported in connection with the rod E to bear against the pole A, this roller serving to facilitate movement of said rod.

55

Springs O have coils thereof on the bolt D, and the ends of these springs extend in opposite directions, their forward ends being connected to the pole-hounds and their rear ends looped over the bolt Q, whereby downward 60 pressure is exerted on the levers F to hold the brake-beam shoes away from the adjacent wheels when the link L is disengaged from the ratchet-bar N aforesaid.

In pivotal connection with the sand-board 65 C of the truck is a drop-hook H, and this hook is put into engagement with the bolt Q whenever it is desirable to prevent operation of the brake mechanism due to backing or holding back of the horses hitched to the wagon, and 70 said hook being engaged with said bolt the pole A is held in horizontal position, its weight being then off said horses. It also follows that the pole may be held up off the ground by the engagement of the hook H and bolt Q 75 when the horses are unhitched from the wagon. The hook being disengaged from the bolt Q, backing or holding back of the horses hitched to the wagon will result in backward movement of the rod E to actuate the levers F, 80 whereby there is pull on the links G and brake-beam to cramp the brake-shoes against the adjacent wheels. At the same time there is engagement of the link L with the ratchet-bar N to hold the brake as tight as it is possible 85 to set the same, there being sufficient length of said bar to compensate for wear of said shoes. The horses being required to pull after setting of the brake, the previously-contracted springs O expand, and thus insure releasing of said brake.

Having now fully described my invention, what I claim as new, and desire to secure by Letters Patent, is—

1. The combination of the brake-beam loose 95 in hangers, the pole, levers fulcrumed on the pivot-bolt of said pole, links connecting said brake-beam and levers, a rod in connection with said levers, a link in connection with the forward end of the rod, a ratchet-bar on the 100

aforesaid pole engaged by the link, and a neck-yoke connected to said link.

2. The combination of the brake-beam loose in hangers, the pole, spring-controlled levers fulcrumed on the pivot-bolt of said pole, links connecting said brake-beam and levers, a rod in connection with said levers, a link in connection with the forward end of the rod, a ratchet-bar on the aforesaid pole engaged by the link, and a neck-yoke connected to said link.

3. The brake-beam loose in hangers, the pole, levers fulcrumed on the pivot-bolt of said pole and connected at their rear ends by

a bolt, links connecting said brake-beam and bolt, a rod having rear branches thereof in connection with the forward ends of said levers, a link in connection with the forward end of the rod, a ratchet-bar on the aforesaid pole engaged by the link, a neck-yoke connected to said link, and a pivotal hook arranged to be engaged with the bolt aforesaid, the engagement of said hook and bolt serving to prevent setting of the brake.

VACLAV FINGOUST.
